UNITED STATES PATENT OFFICE

131,455

DESIGN FOR A HAIR CLASP

Stephen F. Kayn, New York, N. Y., assignor to Ross McFadden, Hollywood, Calif.

Application July 23, 1941, Serial No. 102,389

Term of patent 7 years

To all whom it may concern:

Be it known that I, Stephen F. Kayn, a citizen of the United States and a resident of the Borough of Manhattan, city and State of New York, with a post-office address at No. 45 East 9th Street, in the Borough of Manhattan, city and State of New York, have invented a new, original, and ornamental Design for a Hair Clasp, of which the following is a specification, reference being had to the accompanying drawing, forming part thereof, in which—

The characterizing features of my design reside in a hair clasp having the proportions and configuration disclosed, including arcuate three stepped cut-out portions arranged on opposite sides of the ends of the clasp specifically as shown.

I claim:

The ornamental design for a hair clasp, as shown and described.

STEPHEN F. KAYN.
